UNITED STATES PATENT OFFICE.

CHARLES S. ELLIS, OF CHICAGO, ILLINOIS.

SPRING-UPHOLSTERY WORK.

SPECIFICATION forming part of Letters Patent No. 692,837, dated February 11, 1902.

Application filed November 23, 1900. Serial No. 37,517. (No model.)

To all whom it may concern:

Be it known that I, CHARLES S. ELLIS, a citizen of the United States, residing at Chicago, in the county of Cook and State of Illinois, 5 have invented a new and useful Improvement in Spring-Upholstery Work, of which the following is a specification.

My invention relates particularly to devices for connecting the coiled springs used in such 10 work with the border or edge wires used to form the edge of a couch, cushion, or the like.

The principal object of my invention is to provide a clip which will securely fasten to the border of the frame of a spring couch, 15 bed, chair, cushion, or the like the spiral of the coiled spring used therein, so that the wire-edge of such cushion, couch, bed, or chair may respond to the upward and downward movements of the springs to which the said wire 20 is attached and which at the same time has in combination therewith means for retaining the cord used in upholstery-work for tying the springs to control their upward and lateral motion.

Having the foregoing object in view, the invention consists of a metal clip comprising two body portions straight on one edge and curved on the other edge, a bent neck connecting said body portions, a substantially 25 right-angled flange on each body portion at the straight edge thereof, and a curved flange 30 on each body portion opposite the right-angled flange and disposed along the curved edge.

In the drawings, Figure 1 is a plan view of the corner of a couch, bed, chair, or cushion border attached to spiral springs by means of the clip and the cord through it. Fig. 2 is a view of the under side of the clips, one being 35 clamped over the edge or border of the springs and the other being in position to be so clamped. Fig. 3 is a view of the blank used to make the clip before the edges are turned. Fig. 4 is a view in perspective of one 40 of the springs tied down by the cord to control the upward movement thereof and fastened to the couch-border by the clip. Fig. 5 is a cross-section through wire, spring, and clip on the line 11 in Fig. 1. Fig. 6 is a view 45 of the clip in perspective. Fig. 7 is a cross-section through edge wire, spring, and clamped clip along the line 22 in Fig. 1.

In the construction of a clip according to my design I provide first a blank, preferably of thin sheet metal, such as is shown in Fig. 3, with one of its sides C curving inwardly and with one portion cut not only out of such curving side, but also out of the side S opposite thereto, along the edge thereof, leaving the spaces O and O' midway between the ends of the blank and forming between such spaces the neck N, connecting the parts of the blank referred to by the letters E and E'. In practice I find it desirable to make the edge of the separated parts of the curved side of the blank in the arc of a circle. This blank I shape, preferably, with a die suitable for that purpose into the form shown in Fig. 6, so that the neck N will be rounded and the curved edge C of the blank will be turned over and lie in a plane substantially parallel to the original plane of the underlying main surface of the blank and so that the opposite straight edges S will be turned up as flanges in a plane substantially perpendicular to the original plane of the blank. The shaping is so done and the edges so turned that the portions of the blank turned up along the straight edges thereof are substantially the same in surface as the portions F turned over along the curved side of the blank. This construction is preferred, because it is desired that when the upturned straight-edged portions are clamped over the spring and border-wires, as shown in Fig. 2, the curved and straight edges of the clip will 50 contact each other or approach contact with each other around the spring and border-wires. When so clamped the clip will, along the side represented by the curved edge, form two separated hollow annular flanges F', suitable for the reception therein through the open space between the straight edge (marked S) and the curved edge (marked C) of the spiral-coiled spring-wire W, and along the side represented by the straight edge will form two angles, 55 into which the edge wire W' may be inserted, as shown in Fig. 2, into portions ready to be held therein by the clamping thereover of those portions of the clip marked F and turned up along the straight edge S, hereinbefore referred to. The rounding of the neck N will leave between the clip and the enclosed edge wire and the spring-strand a space 60 sufficiently large to permit of the passage

therethrough of a cord x , such as is commonly used in spring-upholstery work for fastening the springs to each other and to the framework upon which they stand.

5 In use, desiring to fasten the edge wire and the springs in such manner as will put the springs in condition to respond equally and collectively to pressure, I first take an edge or border wire, such as is commonly used in 10 the art for the edge of a couch or cushion, and bring it into contact with the top spiral of the outer rows of the coiled springs W , which said springs are supported by the framework of the article of furniture desired to be 15 upholstered. I then tie the springs to each other, to the edge wire, and to the framework or base upon which they stand, as shown in Figs. 1, 2, and 4, using cords of suitable size and strength. When the border or 20 edge wire has been tied to any given spring, I apply the clip to the top spiral of the spring and to the edge wire, so that cord x will lie beneath the neck N and the spiral will be introduced within the curved or annular flanges 25 of the clip and the wire edges within the angles A of the same. I then apply to the clip a pair of pincers, designed for the purpose of turning the flanges F , and fasten such flanges over the edge wire W' , as shown in 30 Figs. 1, 2, and 7. The border-wire and the springs are thus brought into close contact and fixedly attached to each other over the cord x .

I point out that my clip is an improvement 35 over all other clips used in spring-upholstery work in that it is the only clip yet designed which can be used to fasten together springs and edge wire after the springs are corded and tied in the manner necessary and common 40 in the art.

While I have described my invention with more or less minuteness regarding the details of construction and as being embodied in certain precise forms, I do not desire to be 45 limited thereto unduly or any more than is pointed out in the claims. On the contrary, I contemplate all proper changes in form or

construction and arrangement, the omission of immaterial elements, and the substitution of equivalents as circumstances may suggest 50 or necessity render expedient.

I claim—

1. In a spring couch or cushion, the combination of rows of springs properly supported, a wire border extending around the outer 55 rows of springs, a cord fastening the border to the springs, the springs to each other and connecting them also with their underlying support, and metal clips, fastening the wire border and the springs over the cord, the said 60 clips consisting of two portions, each having one right-angled flange along a straight edge and one curved flange along an inwardly-curving edge and joined together by a neck rounded to fit over the cord, the right-angled 65 flanges being adapted to be bent around the edge wire to connect the wire and springs, all substantially as described.

2. As a new article of manufacture, a metal clip for spring-upholstery work consisting of 70 two body portions, straight on one edge and curved on the other edge, a bent neck connecting said body portions, a substantially right-angled flange on each body portion at the straight edge thereof, and a curved flange 75 on each body portion, opposite the right-angled flange, and disposed along the curved edge.

3. In spring-upholstery work, the combination of a coiled spring and straight-edged wire 80 adjacent thereto, a cord fastening together the spring and the edge wire and a clip clamped over the edge wire, spring and cord, the said clip consisting of two portions each having an angular flange, along a straight edge, and 85 another flange opposite thereto along a curving edge, the two portions being joined by a rounded neck fitting over the cord, all substantially as described.

CHAS. S. ELLIS.
